UNITED STATES PATENT OFFICE.

HENRY C. KIRK, JR., OF BALTIMORE, MARYLAND.

DESIGN FOR A PAPER-KNIFE.

SPECIFICATION forming part of Design No. 25,605, dated June 9, 1896.

Application filed March 3, 1896. Serial No. 577,065. Term of patent 7 years.

To all whom it may concern:

Be it known that I, HENRY C. KIRK, Jr., a citizen of the United States, and a resident of the city of Baltimore, in the State of Maryland, 5 have invented a certain new and original Design for Paper-Knives, of which the following is a specification.

My invention relates to a new and original design for a paper-knife to be used as a letter-opener or for any other similar purpose.

My design is generally executed in silver, but it may be executed in any other material.

Figure 1 is a vertical elevation of the paper-knife, showing the design of the handle and blade. Fig. 2 is an edge elevation of the same. Fig. 3 is a cross-section of the handle.

My design consists in an enfoliated or arrow-shaped blade having barbs at its rear end 20 and a handle which is enlarged at its rear

end and rounded at its rear extremity. The handle is decorated with an embossed design, substantially as shown, generally produced by chasing or engraving. The handle is surrounded with two beads between it and the 25 blade.

Fig. 2 shows the handle of the knife chased on both sides.

Having thus described my new design, I claim—

The design for a paper-knife substantially as shown and described.

Signed at Baltimore city and State of Maryland this 24th day of January, A. D. 1896.

HENRY C. KIRK, JR.
